UNITED STATES PATENT OFFICE

SVEN LINDBERG, OF GALESBURG, ILLINOIS.

WATER-EVAPORATOR.

1,262,068.

Specification of Letters Patent.

Patented Apr. 9, 1918.

Application filed March 30, 1917. Serial No. 153,594.

To all whom it may concern:

Be it known that I, SVEN LINDBERG, a citizen of the United States, and a resident of Galesburg, in the county of Knox and State 5 of Illinois, have invented a new and useful Water-Evaporator, of which the following is a specification.

The invention relates primarily to a device attachable to a hot-air pipe, adjacent a 10 floor-register, and adapted to contain water to be heated by the hot air passing from said pipe to and through the register, whereby to humidify the air in a room.

As the nature of the invention is more 15 fully disclosed it will be evident that its use is not limited alone to hot air systems of heating, but that it may be used with equally as good results in connection with the radiators of steam, vapor and hot water heating equipments.

The principal object of the invention is to improve the construction and to increase the capacity, utility and efficiency of devices of this nature.

25 The invention consists in the improvements hereinafter described.

In the accompanying drawings, which illustrate a preferred and a modified embodiment of my invention:

30 Figure 1 is a perspective view showing the novel evaporator;

Fig. 2, a perspective, one of the side pieces of the water pan removed in order to more clearly show the interior structure;

35 Fig. 3, a vertical longitudinal section showing the evaporator as it appears when in position for use; and

Fig. 4, a plan view.

Considering the drawings in detail and 40 referring to each element and, where necessary, to each part thereof by a distinguishing reference character, 2, 2 designate portions of a floor; 3 indicates an ordinary register-plate removably supported thereby and 45 provided with openings 4 for the passage of air; and 5 denotes a hot-air pipe the box-top of which is provided with flared sides 6, flared ends 7, and a flange 8 operating as an open bottom.

50 The preferred type of my improvements is shown best in Fig. 1, wherein 9, 9 designate the outer, flared end-walls and 10, 10 the outer, flared side-walls of a water-pan 11 the inner side-walls of which are designated by 12 and the inner end walls by 13. The adjacent inner and outer walls are united

at their lower edges whereby to provide a continuous water channel 14.

15, 15 indicate pockets each of which has an open top which communicates with the 60 channel 14 as follows: The side-pieces of each pocket extend upward substantially to the top of the pan 11, but their edges are open. A suitable number of registering slots 16 are cut in each end 13 and the vertical edges of the pocket extensions 17 are soldered one at each side of each slot, to the adjacent wall 12. The water may thus pass freely from the pan, through the several slots 16, into the water-circulating channels 70 18, and thence into the pockets 15.

In operation, the channel 14 having been filled with water a portion thereof will flow through the slots 16, pass between each co-acting pair of pocket-extensions 17 and 75 thence flow into the communicating pockets. Each pocket while of relatively small capacity contains a comparatively great heating surface which is constantly subjected to the hot air coming through the source of 80 supply 5. The pockets being formed of metal, it of course follows that when their portions which lie below the bottom of the pan become heated, the heat will be communicated or pass upward to the extensions 85 17 which will thus aid in heating the water contained in the pan. The water in each pocket thus becomes quickly heated and it will rise and give off moisture. As it rises the pocket will fill with the cooler water, 90 and the heating processes continue in the manner described, the water, it being particularly noted, being constantly circulated. The pan *per se* and the extensions are 95 constantly subjected to the hot air coming from the pipe 5, and they of course become heated thereby and thus maintain in a warm condition all the water contained in the channel and between the extensions. The water will be quickly evaporated and the relative 100 humidity of the air in the room greatly increased, making it much more sanitary and healthful. Dry air being most difficult to heat the device is of considerable economic value as regards fuel consumption. Furniture and musical instruments are damaged 105 greatly by hot, dry air. This is especially true of pianos, the sounding boards of which become cracked, and the veneers and action-parts of which become warped, unglued and checked, whereby the instrument becomes practically worthless.

I claim as new and as my invention the following, to-wit:

1. In an evaporator, continuous inner and outer walls providing a continuous water channel, opposite portions of the inner wall being provided with registering slots, and a plurality of plates attached each to the inner walls and at the edge of one of the slots, each adjacent pair of said plates thus forming a channel communicating with said continuous channel, and the lower portions of each coacting pair of plates united to form a water pocket.
2. In an evaporator, an inner wall comprising sides and ends, the latter provided with registering vertically arranged slots, an outer wall completely surrounding said inner wall and together therewith providing a continuous water-channel, a bottom common to said walls, and a plurality of heating-plates arranged in spaced pairs and attached each to said inner walls and at the edge of one of the slots therein, each adja-

cent pair of said plates forming a channel communicating with said continuous channel and the lower portion of each coacting pair of plates united to form a water pocket.

3. In an evaporator, continuous inner and outer walls providing a continuous water channel substantially rectangular in outline, opposite portions of the inner wall being provided with registering slots, a bottom common to said walls, and a plurality of plates arranged in coacting pairs extending upward to approximately the top of the pan and a short distance below said bottom, each pair of plates secured to said inner wall and providing communication between opposite sides of said continuous channel, and the edges of the lower portions of the pairs of plates united to form water pockets.

In testimony whereof I hereunto set my hand this 27th day of March, 1917.

SVEN LINDBERG.
